US00D333814S

United States Patent [19]

Swanson et al.

[11] Patent Number: Des. 333,814

[45] Date of Patent: ** Mar. 9, 1993

[54] **COMBINED ELECTRONIC DRAWING STYLUS AND TABLET HOUSING**

D. 312,449 11/1990 Komada D14/100
D. 317,151 5/1991 Daly D14/100
D. 319,434 8/1991 Lund D14/100

[75] Inventors: **Lanette O. Swanson, Buffalo Grove, Ill.; Albert Y. Chung Cheung, Hong Kong, Hong Kong**

Primary Examiner—Wallace R. Burke

Assistant Examiner—Freda S. Nunn

Attorney, Agent, or Firm—Dick and Harris

[73] Assignee: **Video Technology Industries, Inc., Wheeling, Ill.**

[57] **CLAIM**

The ornamental design for a combined electronic drawing stylus and tablet housing, as shown and described.

DESCRIPTION

FIG. 1 is a reduced top perspective view of a combined electronic drawing stylus and tablet housing, showing our new design;

FIG. 2 is a right side elevational view thereof;

FIG. 3 is a left side elevational view thereof;

FIG. 4 is a top plan view thereof;

FIG. 5 is a front elevational view thereof;

FIG. 6 is a bottom plan view thereof; and,

FIG. 7 is a rear elevational view thereof.

The cord is shown broken away in the views to indicate indeterminate length.
